DISPLAY BOX OR SIMILAR ARTICLE

Nathan K. Morris, 4th and Railroad, Neptune City, N.J.

Filed Aug. 11, 1960, Ser. No. 61,703

Term of patent 7 years

(Cl. D58—11)

The drawing is shaded to indicate contrasting colored areas.

I claim:

The ornamental design for a display box or similar article, as shown and described.
